UNITED STATES PATENT OFFICE.

EDWIN M. ROSENBLUTH, OF PHILADELPHIA, PENNSYLVANIA.

DESIGN FOR A LANTERN-BODY.

SPECIFICATION forming part of Design No. 27,862, dated November 16, 1897.

Application filed July 1, 1897. Serial No. 643,157. Term of patent 7 years.

To all whom it may concern:

Be it known that I, EDWIN M. ROSENBLUTH, a citizen of the United States, residing in the city and county of Philadelphia and State of 5 Pennsylvania, have invented and produced a new and original Design for a Vehicle-Lantern, of which the following is a specification.

The drawing hereto attached is a view in perspective of a lantern body embodying my 10 design.

As shown in the drawing, the lantern body embodying my design comprehends three 15 divisions or parts, namely: the combustion chamber A, the top or chimney B, and the lamp chamber C.

The combustion chamber is of cylindrical form and disposed with its axis in horizontal 20 position, the rear end of said cylindrical body being closed by a concavo convex web a, embodying a series of small apertures a^x , and a jewel A^x . The front end of the cylindrical body is of flaring or trumpet mouth form, and contains a lens of any usual type.

The top B consists of an upwardly and outwardly flaring neck b embodying apertures 25 b,—a head b', formed as a vertical continuation of said neck and embodying a series

of apertures b^2 ,—and an imperforated cover plate B^x , seated upon said head, said cover plate being shown of concavo-convex form, 30 having the reduced waist b^3 , and a crown b^4 of diameter in excess of that of the waist.

The lamp chamber C, disposed below the combustion chamber, is formed as a cylindrical body, arranged with its axis in vertical 35 position.

The upper portion c' of said lamp chamber is of less diameter than the lower portion c^2 , and, in the vicinity of the upper end of said portion c^2 are formed as a series of elongated 40 wall openings c^3 .

c^4 is an inclosing cup-like device, seated upon the lower end of the lamp chamber.

What I claim is—

A design for a lantern body, substantially 45 as herein shown and described.

In testimony that I claim the foregoing as my invention I have hereunto signed my name this 28th day of June, A. D. 1897.

EDWIN M. ROSENBLUTH.

In presence of—

F. NORMAN DIXON,
THOS. K. LANCASTER.
